(57) **CLAIM**

The ornamental design for a radio module housing, as shown and described.

DESCRIPTION

FIG. 1 is an isometric view of a radio module housing; FIG. 2 is a top plan view of the radio module housing of FIG. 1;

FIG. 3 is a bottom plan view of the radio module housing of FIG. 1;

FIG. 4 is a front elevational view of the radio module housing of FIG. 1;

FIG. 5 is a side elevational view of the radio module housing of FIG. 1, the opposite side elevational view being identical; and,

FIG. 6 is a rear elevational view of the radio module housing of FIG. 1.
